UNITED STATES PATENT OFFICE.

EZRA SECOR, OF ST. JOSEPH, MICHIGAN.

SAFETY DEVICE FOR PRESSES.

Application filed August 7, 1926. Serial No. 127,955.

This invention has for its object the provision of a simple, inexpensive and easily applied device whereby the operator of a 5 punching press or like machine will be guarded against injury to his hands, and the work removed at each operation of the machine without exposing the operator to injury. The invention provides a device which may be applied to any machine having 10 a reciprocating working part, may be easily adjusted to the requirements of any particular case, and will operate in a highly efficient manner in use. The invention is illustrated in the accompanying drawing 15 and will be hereinafter fully described, the novel features being subsequently particularly pointed out in the appended claims.

In the drawing:

Figure 1 is a perspective view of my safety 20 device illustrating the application of the same;

Fig. 2 is a plan view of the adjustable 25 guide, and

Fig. 3 is a detail plan view of the arm supporting the said guide.

In carrying out the invention, I provide a standard or post 1 which is preferably a flat bar having a lateral foot 2 at its lower end adapted to be bolted to the bed plate of a 30 punching press or other machine. A bracket 3 is carried by this post or standard, and a slot 4 is formed in the standard to permit the bracket to be adjusted vertically as may be necessary to fit the device to any particular machine. The bracket is firmly secured in place by set bolts 5 inserted through 35 the slot 4 into the bracket, as shown in Fig. 1. A lateral foot 6 is formed at the lower end of the bracket 3 and at the upper end 40 of the same a cap or angle bracket 7 is secured, the said cap and the foot 6 being provided with circular openings to receive the pivot studs 8 formed at the ends of a strap or flat bar 9 having a helical bend 10 in 45 its upper portion. To the lower end of the strap or bar 9 is secured the laterally projecting flat blade or pusher 11 which is preferably formed of resilient metal and may be of any desired length. Fitting around 50 the strap 9 is an annulus 12 having a radial slot 13 therein and formed at the end of an arm 14, said arm being alined with the said slot 13, as shown clearly in Fig. 3. The arm 14 is bolted to the foot 15 at the lower end 55 of an attaching plate 16 which rises vertically and is provided in its upper portion

with a vertical slot 17 through which a securing bolt 18 is inserted into the plunger head of a punching press or the corresponding part of any other machine. Resting 60 upon the annulus 12 is a disk 19 which is provided with a diametrical open-ended slot 20 and, at opposite sides of said slot with arcuate slots 21, set bolts 22 being inserted through the said arcuate slots to be engaged 65 in openings 23 provided therefor in the annulus 12. The slot 20 is to be arranged so as to fit closely to the opposite faces of the strap 9 and the arcuate slots 21 permit the disk to be adjusted to the twist in the strap 70 so that the resulting rotation will be imparted to the strap at the proper point in the operation of the machine. The slot 13 and the open end of the slot 20 permit the annulus and the disk to be easily engaged 75 about the strap and adjusted thereto, it being noted that the inner diameter of the annulus 12 is slightly greater than the width of the strap so that the annulus does not 80 have any effect upon the rotation or oscillation of the strap.

It is thought the action of the device will be readily understood from the foregoing description, taken in connection with the accompanying drawing. When the plunger of the press moves downwardly, the engagement of the slot 20 in the disk 19 with the spiral twisted portion of the strap will rotate the strap so that the blade 11 will be swung outwardly and, consequently, will 85 push the hands of the operator away from the path of the plunger. The lower straight flat portion of the strap 9 permits the plunger to descend and perform its work without imparting further rotation to the 90 strap and the blade and upon the reverse movement of the plunger the blade will remain at rest until the plunger has cleared the work and the die, whereupon the disk 19 will again engage the spiral 10 and impart 95 a reverse oscillation to the strap and the blade which will thereupon sweep the finished work from the lower die. The interval between the completion of the up stroke of the plunger and the beginning of a second down stroke is utilized by the workmen 100 to place a second blank in position to be acted upon by the machine, and permit return of the blade to a point in front of the lower die so that the blank may be placed 105 behind the blade. The blade, however, will continue to move forwardly so that, if the 110

workman should not promptly remove his hands, the blade will push them out of the path of the plunger.

My device is obviously simple in construction and may be produced and applied at a very low cost. The parts are very compact in their arrangement so that the device may be applied in a restricted space without requiring any alteration of the machine to accommodate it, and it will operate entirely automatically with the machine and will serve to efficiently guard against injury to the operator's hands and relieve the operator of the necessity of removing the finished work. The construction of the supporting standard, the attaching arm and the parts for imparting oscillation of the blade is such that they may be very easily and readily adjusted to the requirements of any particular machine.

Having thus described the invention, I claim:

1. A device for the purpose set forth comprising a support, a vertically disposed strap having its ends fitted pivotally in the support, the greater lower portion of the said strap being flat and straight and the

upper portion of the strap having a spiral twist therein, a vertically adjustable arm constructed to be attached to a working part 30 of a machine and encircling the strap, and a member carried by said arm and provided with a slot, the walls of which engage the sides of the twisted portion of the strap whereby reciprocation of said arm will oscillate the strap.

2. A device for the purpose set forth comprising a support, a flat strap disposed vertically and having its ends pivotally engaged in the support, the strap being provided with a spiral twist in its upper portion, a blade extending laterally from the lower end of the strap, an arm to be secured to the working part of a machine and having an annulus encircling the strap, and an actuating disk secured upon the annulus and 40 rotatably adjustable thereon with respect to the strap, the said disk having a diametrical slot fitting closely to the sides of the strap whereby reciprocation of the arm cooperating with the twist in the strap will oscillate the strap.

In testimony whereof I affix my signature.
EZRA SECOR. [L. S.]
